UNITED STATES PATENT OFFICE.

EUGENE D. MERWIN, OF SEATTLE, WASHINGTON.

SAND WASHER AND SEPARATOR.

1,410,340.

Specification of Letters Patent. Patented Mar. 21, 1922.

Application filed February 16, 1920. Serial No. 358,899.

To all whom it may concern:

Be it known that I, EUGENE D. MERWIN, a citizen of the United States, residing at Seattle, in the county of King and State of Washington, have invented certain new and useful Improvements in Sand Washers and Separators, of which the following is a specification.

My invention relates to improvements in apparatus for washing and grading sand and gravel and the object of my improvement is to provide a device of this nature that will separate the gravel from the sand and that will separate and grade the sand with respect to size and will wash the sand thoroughly thereby removing all clay and earthy matter.

Another object is to provide a sand washing and grading device that is constructed and arranged so that the water that is discharged therefrom will be practically free from all fine sand, clay and earthy matter that would tend to settle in pipes or flumes through which the discharge water is removed from sand washer.

A further object is to provide conveyor means for removing the refuse matter from the sand box and to provide automatic devices for opening a discharge orifice and flushing off the refuse comprising the very fine sand, clay and earthy matter when the water in the sand box rises above a predetermined level.

A still further object is to provide means for governing the discharge of sand into the box and to provide means for utilizing the power of a descending stream of water sand and gravel for driving certain parts of the separating device.

Other novel features reside in the means for controlling the inlet of water to the sand box and in the cylindrical screen having a telescopically adjustable casing thereover to govern the discharge of water.

The invention consists in the novel construction, adaptation and combination of parts of a sand washer and separator as will be more clearly hereinafter described and claimed.

In the accompanying drawings Figure 1 is a view in vertical section of a sand and gravel washer and separator constructed in accordance with my invention; Figure 2 is a sectional view of the bottom portion of the same substantially on a broken line 2, 2 of Figure 1; Figure 3 is a view in cross-section

substantially on a broken line 3, 3 of Figure 2; Figure 4 is a detached view in elevation of a bucket wheel into which the sand is delivered as it enters the sand box; Figure 5 is 60 a view partly in section and partly in elevation substantially on a broken line 5, 5 of Figure 4 and Figure 6 is a view in cross section on broken line 6, 6 of Figure 5.

Like reference numerals designate like parts throughout the several views.

Referring to the drawings, the numeral 7 designates a rectangular box provided in its upper portion with an inclined grating 8 upon which water, sand and gravel may be 70 delivered by a rotary wheel 9 that is arranged to receive the said water sand and gravel from a chute 10 and that serves to spread the same out and distribute it more evenly over the grating 8 than would ordinarily be possible if the said water, sand and gravel were delivered directly from the chute 10 onto the grating.

As the gravel passes downwardly over the grating 8 the smaller stones and sand will 80 all pass through such grating and drop onto a screen 11 directly therebelow while the larger stones will pass over the grating and may be discharged through a chute 12.

The sand and pea gravel will drop through 85 the screen 11 onto a pea gravel screen 13, while the graded gravel will be discharged through a chute 14 at the end of the screen 11. The sand will drop through the pea gravel screen 13 into a hopper 15 while the 90 pea gravel which is usually a waste product may be discharged through a chute 16.

All of the above mentioned parts may be of the usual standard form of construction, this invention residing in the sand washer to 95 be hereinafter explained, which, together with the gravel separator, forms a complete working machine.

From the hopper 15 the sand and water are discharged into the buckets 17 of a wheel 100 18 from which they are dumped without unnecessary agitation into the upper end of a passageway 20 in the sand box.

The buckets 17 are preferably made of triangular cross sections as shown in Figures 5 and 6 so that they will cause as little agitation as possible to the water and instead of tending to create a downward current of water in the passageway 20 will tend to crowd such water sidewise against 110 a vertically adjustable screen 21 that is fine enough to prevent the passage therethrough.

of particles of sand and clay but will permit the passage of water.

The wheel 18 is preferably made in the form of a disk that is secured to a shaft 22 and the buckets 17 are removably bolted to the disk.

As the sand descends through the passage-way 20 it is washed by water that is emitted from perforations 23 in transverse pipes 10 24, the direction of flow of such water being substantially at right angles to the direction of movement of the sand.

The larger and heavier particles of sand continue in almost a direct path to the bottom of the box while the finer and lighter particles are deflected toward the discharge side of the box according to their size and specific gravity, the lighter particles of very fine sand, clay and earthy matter settling 15 20 at the farther side of the box.

The sides of the sand box preferably converge toward the bottom as shown in Figure 1 so that the sand settles into a hopper shaped receptacle 25. The upward current 25 of water is strongest near the bottom of such receptacle owing to the fact that the cross sectional area of the hopper decreases toward the bottom.

Extending lengthwise of the hopper shaped receptacle 25 a short distance from the bottom thereof is a pipe 26 having perforations in the top thereof to direct jets of water upwardly and having other perforations in the sides thereof to direct 30 35 jets of water sidewise to thereby keep the material in the bottom of the hopper slightly agitated and prevent it from settling or packing in a solid mass.

Disposed above the pipe 26 in an inclined 40 45 position is another pipe 27 having perforations on its upper side for directing jets of water upwardly and toward the discharge side of the box. The pipe 27 is preferably arranged so that it may be adjusted into different angular positions by raising or lowering the end thereof that is nearest the inlet side of the sand box.

The pipes 26 and 27 together with the pipes 24 may be regulated to control the 50 55 direction of flow of the currents of water within the box thereby controlling the separation of the sand. The vertical adjustment of the screen 21 also effects the distribution and grading of the sand. In practice it is preferred to construct the screen 21 so that it may be entirely removed from the box and a solid adjustable partition wall substituted in its place.

Disposed longitudinally within the upper 60 portion of the hopper shaped receptacle is a cylindrical screen 28 of very fine mesh that is wound upon and supported by a framework or inner cylindrical screen 30 of greater strength and coarser mesh. The 65 cylindrical screen 28 preferably extends en-

tirely across the hopper 25 and is secured to the shaft 22 so that it will be rotated by the turning of such shaft. The rotation of the screen 28 keeps the meshes washed clean of dirt and clay and prevents the 70 screen from becoming clogged so that the water cannot pass therethrough.

A discharge opening 31 is provided in the wall of the sand box within the boundaries of the end of the screen so that 75 all water that is discharged therethrough must first pass through the fine mesh of the screen thereby making it impossible for particles of fine sand, clay and the like to be carried over with the water. 80

The outer end of the shaft 22 is preferably provided with a disk 32 against which the discharging water may flow to counteract the end thrust on such shaft occasioned by the movement of the angularly 85 shaped buckets 17 through the water.

The cylindrical screen 28 is provided with an adjustable and extensible jacket comprising a plurality of telescopic sections 33 preferably of sheet metal that fit snugly 90 thereover and may be adjusted to govern the direction of flow of the currents of water within the sand box. The screen 28 will preferably be made slightly larger near the discharge end so that the larger outer 95 jacket sections 33 will fit snugly thereon.

The discharge water may be carried away through a flume 34.

35 is a screen of fine mesh that is provided in the discharge side of the sand box 100 near the bottom thereof and 36 is an adjustable gate arranged to regulate the area of effective opening through such screen.

The gate 36 will ordinarily be regulated to permit the discharge of a relatively small 105 amount of water through the screen 35.

Disposed flush with the bottom of the hopper and just below the screen 35 is a relatively large refuse discharge pipe 37 whose outer end is arranged to be opened by the 110 lowering and closed by the raising of a gate 38. The bottom end of the gate 38 is connected with a weight 40 by which the gate will be lowered to open the discharge pipe 37 as hereinafter explained while the top 115 end of the gate 38 is connected with a cable 41 that passes upwardly over pulleys 42 and 43 and thence downwardly and is secured to a float 44 that floats upon the water in the sand box. If an excess of clay and 120 refuse accumulates in the end of the hopper 25 it will usually clog the screen 35 thus checking the flow of water through such screen and causing the water to rise to a higher level in the sand box thus lifting the 125 float 44 and lowering the gate 38. As soon as the gate 38 is opened the refuse will be discharged or flushed out through the pipe 37 thus permitting the water to again discharge through the screen 35. As the water 130

level in the sand box is lowered the float 44 will move downwardly and will lift the gate 38 and close the pipe 37.

The graded or classified material in the bottom of the hopper 25 is drawn off through openings 45 that are each arranged to be opened and closed by a separate gate 46. Two separate conveyors 47 and 48 arranged side by side are provided below the openings 45 one of such conveyors being adapted to convey away the washed and graded sand and the other conveyor being adapted to convey away the refuse. The conveyors may discharge into separate hoppers or chutes 50 and 51 as shown in Figure 3. The refuse will collect at the discharge side of the box and will ordinarily be drawn off through the two openings 45 nearest to that side.

The conveyors 47 and 48 may be of the well known link belt and slat or bucket type and are preferably driven by the power derived from the discharging material that comes down the chute 10 and drives the wheel 9. The shaft on which the wheel 9 is mounted may be connected by a sprocket chain 52 with the shaft 22 which shaft 22 may be connected by bevel gears 53 with a shaft 54 that is connected with other bevel gears 55 that serve to drive the conveyors. The impulse of the sand and water in the buckets 17 also helps to drive the shaft 22 and conveyors 47 and 48. If additional power is needed it may be supplied in any well known manner.

The operation of my sand washing and grading machine is as follows: Sand and water from the chute 15 is delivered into the buckets of the wheel 18 and is dropped by these buckets with comparatively little agitation into the water in the passageway 20. As the sand moves downwardly toward the bottom of the sand receptacle, it is subjected to the action of the water from the pipes 24 moving in a direction at substantially right angles to the direction of movement of the sand. The water washes out any dirt and impurities from the sand and by reason of its movement toward the discharge end of the box, carries or deflects the sand toward the discharge end of such box, the larger particles of sand settling more rapidly in the current of water and the smaller particles settling more slowly and being deflected a greater distance toward the discharge end of the box so that the sand is graded with respect to the size of the grains the coarser sand collecting in the bottom of the hopper shaped box near the inlet end and the finer particles collecting in the bottom of such hopper near the discharge end.

The current of water near the outlet end of the box will not be as strong as the current in other places and the very fine sand and silt will settle at the extreme discharge end of the hopper shaped receptacle and

may be removed through the discharge pipe 37. The water that passes through the screen 28 and is discharged through the chute 34 will be practically free from fine sand and silt that would tend to settle in pipes and sewers so that such water may if desired be discharged into a city sewer without danger of clogging the same. The grains of sand that are deposited in the bottom of the hopper shaped box will be of gradually decreasing size from inlet to discharge end of such box so that by drawing off sand at different points along the length of such box different grades of sand may be obtained.

In operation my sand washer is efficient both in washing and in grading the sand, and the water that is discharged from the same is practically free from heavy solid matter that will settle and clog a sewer or flume into which the water empties.

The machine has a large capacity in proportion to its size and the arrangement of the conveyor system permits the material to be discharged constantly from the hopper thus eliminating any danger of clogging.

The conveyors 47 and 48 being connected to the shaft on which the impulse wheel 9 is mounted serve as a speed governor insuring a steady motion to such wheel and making possible the more even discharge of material onto the grating 8.

It will be understood that changes in the form, dimensions and arrangement of parts of this device may be made within the scope of the following claims.

What I claim is:

1. A sand washer and grader comprising a V shaped receptacle having discharge openings arranged at intervals along the bottom thereof, a vertically adjustable screen disposed near one end wall of said receptacle to leave a narrow passageway between it and said end wall, a plurality of water pipes disposed near said end wall and perforated to deliver jets of water toward said screen, means for introducing sand at the top of said passageway and a water supply pipe arranged to extend lengthwise along the bottom of said receptacle and having a pivotal connection near the discharge end of said receptacle whereby it may be adjusted into various angular positions, said water supply pipe having perforations in the upper side thereof.

2. A sand washer and grader comprising a V shaped receptacle having discharge openings arranged at intervals along the bottom thereof, a vertically adjustable screen disposed near one end wall of said receptacle to leave a narrow passageway between it and said end wall, a plurality of water pipes disposed near said end wall and perforated to deliver jets of water toward said

1 screen, means for introducing sand at the upper end of said passageway, a water pipe disposed lengthwise of said receptacle at a short distance from the bottom thereof and 5 arranged to direct jets of water upwardly, a discharge conduit in the upper portion of said receptacle and a fine mesh rotary cylindrical screen having one end that registers with said discharge conduit and through 10 which water must pass to reach said discharge conduit.

3. A sand washer and grader of the class described comprising a relatively long V shaped receptacle having a plurality of 15 openings arranged at intervals along the bottom thereof, a vertically adjustable screen arranged near one end of said receptacle, means for delivering sand into the passageway between said screen and the end wall of 20 said receptacle, a plurality of perforated water pipes arranged along the end wall of said receptacle to direct horizontal jets of water into said sand as it descends through said passageway, a perforated water pipe extending lengthwise of said receptacle in close proximity to the bottom thereof for directing jets of water upwardly, another 25 perforated water pipe inclined with respect to the bottom of said receptacle and adjust-

able into various angular positions, a cylindrical rotating screen disposed in the upper portion of said receptacle and having a discharge opening for water within the boundaries of one end thereof and an adjustable telescopic jacket arranged to fit over and be 35 moved lengthwise along said screen.

4. Means for controlling the outlet of water from a sand washer and grader comprising a screen of fine mesh mounted for rotation in the upper portion of a sand box, 40 a discharge conduit registering with one end of said screen and an extensible and adjustable jacket provided on said screen to vary the effective area of the screen and the location at which the water enters the screen. 45

5. Means for controlling the outlet of water from a sand washer and grader comprising a screen of fine mesh mounted for rotation in the upper portion of a sand box, 50 a discharge conduit registering with one end of said screen and an extensible and adjustable jacket provided on said screen to vary the effective area of the screen and the location at which the water enters the screen.

Signed at Seattle, Washington, this 5th 55 day of February, 1920.

EUGENE D. MERWIN.
